UNITED STATES PATENT OFFICE

PHILIP J. MARTIN, OF ELIZABETH, NEW JERSEY

CABLE GRIP

Application filed March 16, 1928. Serial No. 262,211.

The invention relates to improvements in woven cable grips. These grips are well known in the art and consist of a plurality of strands of wire or wire cord woven into an open mesh hollow body, cylindrically shaped and with means on one of their ends for attaching a draw rope.

In the installation of cables it is the present practice to use two grips, a pulling grip and a luffing grip. The pulling grip is used to draw the cable through the duct and the luffing grip is used for luffing or pulling the slack of the cable into the manhole. Each grip is made as a complete article of manufacture, that is a mesh is made up with one set of eyes or suitable fixtures at its end to which the pulling rope may be attached for pulling the cable, and a different arrangement of eyes or fixtures is permanently secured to the end of another mesh for luffing purposes. The mesh part is the first part of the grip to wear out and when the mesh has outlived its usefulness the entire grip must be discarded and a new one purchased.

The object of the present invention is to provide an interchangeable mesh that may be used with suitable heads for either a pulling grip or a luffing grip. A device of this character has numerous advantages over the present type of cable grip. A user makes an initial purchase of the pulling head and luffing head and interchangeable mesh. As previously stated the mesh is the first part to wear out. The heads being substantial strong members will last almost indefinitely and the mesh will be the only part that is necessary to renew thus making for considerable economy as the permanent fixtures or eyes on either the pulling or luffing grip quite often cost more than the mesh itself.

In the installation of cable the grip with the pulling head is used to draw the cable through the duct. When the manhole is reached and it is desired to luff or pull the slack into the manhole it is only necessary to remove the pulling head and substitute the luffing head. This may be done without removing the mesh from the cable thus saving a great deal of time and labor in the installing. In the present practice it is necessary

to remove the entire pulling grip and attach the luffing grip when the manhole is reached and it is desired to luff the cable.

Other objects and advantages will become apparent as this specification proceeds. In 55 the drawings forming a part thereof one embodiment of the invention is illustrated. Referring to said drawings:

Fig. 1 is an elevation of the interchangeable woven open mesh cable grip; 60

Fig. 2 is a fragmentary view looking at right angles to Fig. 1 and showing the upper part of the grip;

Fig. 3 is a longitudinal sectional view through the pulling head; 65

Fig. 4 is an elevation looking at right angles to Fig. 3 with part of the removable retaining plate broken away;

Fig. 5 is a cross sectional view taken on line 5—5 of Fig. 3; 70

Fig. 6 is a side elevation of the luffing head;

Fig. 7 is a view of the luffing head looking at right angles to Fig. 6; and

Fig. 8 is a cross sectional view taken on line 8—8 of Fig. 7. 75

Referring again to the drawings the reference numeral 10 designates the interchangeable woven open mesh cable grip. Grips of this general type being well known it is not thought necessary to enter into a detail description at this time. The grip is formed of a plurality of strands of wire or wire cord 11 which are woven into an open mesh hollow body, cylindrically shaped. The gripping action of these grips is due to the change of form of the meshes. When a pull is exerted the meshes are elongated axially and are narrowed circumferentially, thus decreasing the diameter of the grip and causing it to firmly grasp the cable. 85

The wires at one end of the grip are divided so as to form two loops or tugs 12. These loops 12 are preferably formed so as to be absolutely free, that is, with no winding wrapped about them. This allows the stresses and strains to be evenly distributed over all the wires of the grip. However the invention in its broad aspect would not be limited to this construction, for example, in- 95 100

stead of the loops or tugs 12 illustrated, the wires might be secured to a suitable fitting with an eye formed therein to serve the same function as the loops or tugs. While two loops or tugs 12 are illustrated under some conditions it might be desirable to provide more.

The pulling head 13 illustrated in Figs. 3, 4 and 5 will now be described. As shown it is a solid substantial member and round in cross section so as to readily pass through a duct without catching on any projecting or rough edges. However it might be hollowed out for lightness and assume quite a different shape and still perform all its desired functions.

One end of the pulling head 13 is tapered as indicated at 14 and is provided with an eye 15 to which the draw rope is attached.

At the region of the large diameter the opposite sides are flattened as at 16. Projecting from these flattened portions are lugs 17 about which the loops or tugs 12 are placed. To insure the loops 12 from slipping off the lugs 17 retaining plates 18 are provided. These retaining plates are preferably so shaped as to complete the cylindrical contour at the flattened sides of the pulling head.

Means of any suitable character may be provided for removably securing the retaining plates 18 in position. As illustrated a plug 19 having a countersunk head passes through an opening 20 in the lugs and body of the pulling head. A screw 21 is threaded into this plug from the opposite side, thus holding both plates in position in such a way that they may be easily and quickly removed or replaced, for attaching or removing the loops 12 from the lugs 17 when it is desired to change from the pulling head to the luffing head or vice-versa.

The luffing head 25 illustrated in Figs. 6, 7 and 8 will now be described. The luffing head is preferably a trough-like member having its end tapered at 26 for lightness and its opposite end 27 tapered for lightness and also as an aid in accommodating the loops 12 of the mesh 10.

Near what might be termed the forward end 27 are positioned at opposite sides the lugs 28 about which the loops or tugs 12 pass when the luffing head is in use. Washers 29 held in place by screws 30 prevent the loops or tugs from slipping off the lugs 28. An eye 31 on the under side of the luffing head forms a means for attaching the draw rope.

In the operation of the device the mesh is placed about the end of the cable and the pulling head is secured to the loops or tugs 12. The draw rope which is made fast to the eye 15 of the pulling head drags the cable through the duct until a manhole is reached. It is then advisable to take up the slack in the cable. The screw 21 and plug 19 are loosened allowing the retaining plates 18 to

be taken off and the pulling head removed, without removing the mesh from the cable. The luffing head is then substituted for the pulling head and the slack taken up in the cable. The luffing head is preferably trough shaped so as to provide a rest for the cable. Due to the fact that the luffing head is used almost entirely in the manholes it is not essential that it be of a shape to freely pass through the ducts. This is of course quite necessary with the pulling head. The shapes of both the luffing and pulling heads might vary widely and still perform their desired functions.

Changes such as those set forth and others that would occur to one skilled in the art might be made in arrangements of parts and details of construction without departing from the spirit of the invention or the scope of the appended claims.

What I claim is:

1. A pulling head for an interchangeable woven open mesh cable grip formed of a plurality of strands brought together at the draft end into a pair of freely formed loops, said pulling head being provided with a pair of lugs to engage said freely formed loops, retaining means cooperating with said lugs to maintain said loops in position and removable holding means for said retaining means.

2. A luffing head for an interchangeable woven open mesh cable grip formed of a plurality of strands brought together at the draft end into a pair of freely formed loops, said luffing head being trough-shaped and provided with a pair of lugs to engage said freely formed loops, retaining means cooperating with said lugs to maintain said loops in position and removable holding means for said retaining means.

In testimony whereof I affix my signature.

PHILIP J. MARTIN.
